UNITED STATES PATENT OFFICE.

HOWARD MAXWELL, OF SCHENECTADY, NEW YORK, ASSIGNOR TO GENERAL ELECTRIC COMPANY, A CORPORATION OF NEW YORK.

CONTROL OF ALTERNATING-CURRENT MOTORS.

No. 918,688.

Specification of Letters Patent. Patented April 20, 1909.

Application filed February 14, 1906. Serial No. 301,029.

To all whom it may concern:

Be it known that I, HOWARD MAXWELL, a citizen of the United States, residing at Schenectady, in the county of Schenectady and State of New York, have invented certain new and useful Improvements in Control of Alternating-Current Motors, of which the following is a specification.

This invention relates to the control of alternating-current motors and has for its object the provision of a device for starting motors of the induction type and bringing them up to running speed in a reliable, safe and efficient manner.

More specifically, my invention relates to the starting of single-phase motors of the induction type. This type of motor, as is well-known, will not start from rest without the employment of special starting devices, such as auxiliary starting windings, or phase-splitting devices connected in the motor circuit, or both. Devices of this character are designed to be in circuit only for a short period, during which the motor is being brought up to synchronism, and if left in circuit too long will become overheated. Means have, therefore, been employed for changing the connections so as to cut out these auxiliary starting devices. In the case of motors with three-phase windings which are to be operated on single-phase current, it has been the practice to use a triple-pole double-throw switch, which, when thrown in one position, starts the motor with its windings Y connected, with the addition of a resistance reactance device for producing a displaced phase at the third terminal. After the motor has been brought up to speed, the switch is thrown into the opposite position, which cuts out the resistance-reactance device and places the motor with its windings delta connected directly on the line. With an arrangement of this character there is nothing to prevent the operator from throwing the switch into the starting position and leaving it there, or from throwing the switch into the running position directly, without passing through the starting position. Moreover, this type of device provides no means of throwing the switch into the off position on failure of voltage, so as to protect the motor upon the return of voltage to the line. In carrying out my invention, I, likewise, provide a resistance-reactance device, but instead of cutting

these devices out of circuit directly upon the motor attaining the running speed, they are cut out gradually step by step, and for this purpose they are so arranged that they can be thus cut out without short-circuiting the line. The resistance and reactance are divided into sections and provided with contacts adapted to be engaged by the pivoted controlling arm, as is common in starting rheostats. The resistance and reactance are in series with different phases of the motor and are concentrically arranged so that the sections of each are cut simultaneously and proportionately so as to maintain the proper dephasing effect during starting, thereby securing a good torque from rest to full speed. In the cutting out of the reactance step by step, it is undesirable, and, in fact, somewhat dangerous to short-circuit a section or sections thereof, and I, therefore, provide means whereby the controlling element makes a quick break with the contact and moves quickly to the next contact, the entire circuit being broken at each step. The controlling arm is pivoted in a manner similar to the controlling lever of a starting rheostat and is biased to the off position, while a no voltage magnet retains it in the running position.

In the accompanying drawing, I have illustrated a device embodying my invention, but it should be understood that this is illustrative merely and that many changes and variations may be made by those skilled in the art without departing from the spirit of my invention.

Referring to the drawing, 1 represents an insulating base of slate, or soapstone, having mounted thereon a series of contacts 2 and 3 arranged concentrically about 4 as a center. The contacts 2 form terminals for a series of resistances 5, while the contacts 3 are similarly connected with the sections of a reactance 6. The controlling lever 7, pivoted at 4, is adapted to sweep over and successively engage the contacts 2 and 3. The insulating segments 8 and 9 are arranged to engage the starting arm when in initial position, and an insulating segment 10 is arranged adjacent to the contacts 3 for purposes hereinafter set forth. In order to prevent the short-circuiting of any of the sections of the reactance 6, the contacts 3 are separated some distance from each other and the insulating contacts 11 are set between them, so as to form a

bearing surface for the contact arm. The brush 11' is arranged so that it can not bridge any two of the contacts 3, and as the circuit is broken at each contact it is essential that a quick break be employed. This quick break may be accomplished by any of the well-known devices for this purpose. In the drawing I have illustrated one method by which this may be carried out, but the particular means whereby this is accomplished is no part of my invention and may be varied at will.

A ratchet wheel 12 is rotatably mounted on pivot 4 and is prevented from movement in a clockwise direction by means of the pawl 13 pivoted at 14 and having a bearing face 13', the contour of which corresponds with that of the tooth which engages the beveled face 14' of the teeth to act as a stop. The spring 15 has one end secured to the pawl 13 and the opposite end secured to the lever 7, the intermediate portion being wound around the pivot 4, thus forcing the lever and pawl toward each other. The controlling lever 7 comprises two portions; the operating arm proper, provided with the handle 16; and the contact portion 17; both of which are independently pivoted at 4. The end of the operating arm opposite the handle 16 is yieldingly connected with the contact arm 17 at 18 by means of a spring 19. A pawl, or bolt, 20, having a slot 21, is arranged to receive the pins 22 fixed in the arm 17 whereby the bolt may slide longitudinally of the arm. A pin 23, secured to the bolt, engages a diagonal slot 24 in the arm 7. The lower end of the bolt 20 is made in the shape of a tooth to engage the teeth of the ratchet wheel 12 to lock the same. It will be seen that when the handle 16 is moved in a clockwise direction the pin 23 will be forced outward from the center 4, carrying with it the bolt 20. The handle 16, however, is moved some distance from the arm 17 before the bolt 45 finally disengages from the teeth of the wheel, and a tension is thereby put on the spring 19. The distance which the handle 16 moves while the bolt is moving out from the teeth is substantially the distance between the contact studs, so that when the bolt finally releases the arm 17 quickly moves in response to the tension of the spring 19 to a position on the next contact. The arm 17 likewise carries a brush 17' for 55 engaging the contacts 2, but in this case the contacts are short-circuited, as is usual in rheostat practice. A no-voltage release magnet 25 is connected in circuit with the motor either across the main phase or across one of the other phases of the motor, and controls an armature 26 pivoted at 27, having a slot 28 adapted to engage a pin 29 on the arm 17 when the latter is moved to the running position, the armature being normally pressed away from the magnet by

means of the compression spring 30. A stop 31 forms an abutment for the controlling arm when in the off position.

The operation of my device will be clearly understood from the foregoing description. In the off position the pawl 13 rests upon the point of one of the teeth of wheel 12 and the brushes 11' and 17' engage the insulation segments 8 and 9. When it is desired to start the motor the handle 16 is moved to the left. Wheel 12 and arm 17 both move with the handle until the face 13' of pawl 13 engages the adjacent tooth. This locks the wheel and likewise arm 17 through bolt 20. The handle is moved along, however, putting a tension on the spring 19 and gradually sliding the bolt 20 out from engagement with the teeth of the wheel 12. When the arm is moved a distance equal to the distance between contacts, the bolt 20 releases the arm 17, which snaps over to the next stud. In this manner the contacts are passed over, gradually cutting out the resistance 5 and the resistance 6 proportionately. The brush 11', which engages the contacts 3, finally passes on to the insulating segment 10, breaking the reactance circuit while the brush which engages the contacts 2 completes the circuit through the last resistance contact. The purpose of breaking the reactance circuit before it is entirely cut out is to avoid short-circuiting phase B of the motor winding, which would occur if both resistance and reactance were reduced to a very small quantity before opening the circuit of either. When the arm reaches the running position, that is, in engagement with the last contact 2, it is held there by the engagement of the slot 28 and pin 29. Upon failure of voltage the armature 26 is released and the arm flies back in response to the tension of the spring 15, carrying with it the wheel 12, which ratchets over pawl 13.

The direction of the current is as follows: When the arm is moved onto the first of the starting contacts current passes from the line through the conductor 32 to pivot 4, thence through the arm 17 to the resistance 5 and reactance 6. From the resistance 5 current passes through conductor 33 to one terminal of the three-phase winding of the motor M at 34, thence through the motor winding to the line L' at 35. A branch from the reactance 6 passes through conductor 36, to a second motor terminal at 37, thence through the motor winding to the line L' at 35. A phase displacement of the current is thus produced in the three portions A, B and C of the three-phase winding which starts the motor, and when the motor is finally in running condition the reactance circuit is broken at 10, as above described, and the motor is connected as a single-phase motor directly across the line. It will be seen that the resistance and reactance are connected in series with

two of the terminals respectively of the three-phase winding of the motor, this connection permitting these devices to be cut out of circuit step-by-step without short-circuiting the line as would be the case if the devices were connected in shunt to the motor.

While I have described my invention in connection with a particular type of mechanism and likewise a particular type of motor, it should be understood that I do not limit my invention as to the mechanism employed nor to the winding arrangement of the motor, except as it is limited by the claims annexed to and forming a part of this application.

What I claim as new and desire to secure by Letters Patent of the United States, is,

1. In combination with a single-phase source of current, an induction motor having a three-phase winding, devices having different impedance factors connected in series with two phases of the motor winding, and means for simultaneously varying the impedance of said devices step by step.

2. In combination with a single-phase source of current, an induction motor having a three-phase winding, a resistance and a reactance connected respectively in series with two phases of the motor winding, and means for simultaneously reducing the impedance thereof step by step.

3. The combination with a single-phase source of current and an induction motor having a three-phase winding, of means for starting the said motor comprising a resistance and a reactance each divided into sections and provided with contacts arranged concentrically, a controlling element adapted to engage said contacts, and means for causing a quick break between said element and the contacts.

4. The combination with a single-phase source of current and an induction motor having a three-phase winding, of means for starting the said motor comprising a resistance and a reactance each divided into sections, a controlling arm therefor biased to the off position, means whereby said controlling arm is given a quick break from one section to another, and a no-voltage magnet for holding the arm in running position.

5. In combination with a single-phase source of current, an induction motor having a three-phase winding, two devices of different impedance factors, means for connecting one terminal of the motor winding to one

terminal of the source and connecting the other two terminals of the winding through said two devices respectively to the other terminal of the source, and means for cutting 60 said devices out of circuit step-by-step.

6. In combination with a source of single-phase current, an induction motor having a three-phase winding, a resistance, a reactance, means for connecting one terminal of 65 the motor winding to one terminal of the source and connecting the other two terminals of the motor winding through the resistance and reactance respectively to the other terminal of the source, and means for cutting out said resistance and reactance step-by-step.

7. In combination with a source of single-phase current, an induction motor having a three-phase winding, a resistance, a reactance, means for connecting one terminal of 75 the motor winding to one terminal of the source and connecting the other two terminals of the motor winding through the resistance and reactance respectively to the other terminal of the source, and means for simultaneously cutting out proportionate portions of said resistance and reactance step-by-step.

8. In combination with a source of single-phase current, an induction motor having a polyphase winding, two devices of different impedance factors connected between one terminal of the source and two different phase terminals of said winding, and a 90 switch arranged to cut portions of said devices out of circuit and then to break the circuit of one device and cut the remainder of the other device out of circuit.

9. In combination with a source of single-phase current, an induction motor having a three-phase winding, a resistance connected between one terminal of said winding and one terminal of the source, a reactance connected between a second terminal of said 100 winding and the same terminal of the source, and a switch arranged to cut portions of both resistance and reactance out of circuit, then to break the circuit of one of these and cut the remainder of the other out of circuit. 105

In witness whereof, I have hereunto set my hand this 13th day of February, 1906.

HOWARD MAXWELL.
